US0D1019485S

(12) **United States Design Patent** (10) Patent No.: **US D1,019,485 S**
(45) Date of Patent: ** Mar. 26, 2024

(54) **VEHICLE REAR FASCIA**

(71) Applicant: **GM GLOBAL TECHNOLOGY OPERATIONS LLC**, Detroit, MI (US)
(72) Inventor: **Brian Malczewski**, Royal Oak, MI (US)
(73) Assignee: **GM Global Technology Operations LLC**, Detroit, MI (US)

(**) Term: **15 Years**

(21) Appl. No.: **29/776,692**

(22) Filed: **Mar. 31, 2021**

(51) LOC (14) Cl. **12-16**
(52) U.S. Cl. **USPC D12/167**

(57) **CLAIM**

The ornamental design for a vehicle rear fascia, as shown and described.

DESCRIPTION

FIG. 1 is a front and left perspective view of a vehicle rear fascia showing my new design;

FIG. 2 is a front elevation view of the vehicle rear fascia of FIG. 1;

FIG. 3 is a left elevation view thereof;

FIG. 4 is a right elevation view thereof;

FIG. 5 is a top view thereof;

FIG. 6 is a back elevation view thereof; and,

FIG. 7 is a bottom view thereof.

The broken lines in the drawings depict portions of the vehicle rear fascia that form no part of the claimed design.
